FIG. 4.

UNITED STATES PATENT OFFICE.

MATHIAS R. KONDOLF, OF ROCHESTER, NEW YORK, ASSIGNOR, BY MESNE ASSIGNMENTS, TO FI-BO-PAK COMPANY, OF PHILADELPHIA, PENNSYLVANIA, A CORPORATION OF DELAWARE.

COVER-PLACING APPARATUS FOR BOXES.

1,410,575.

Specification of Letters Patent. Patented Mar. 28, 1922.

Application filed April 23, 1919. Serial No. 293,233.

To all whom it may concern:

Be it known that I, MATHIAS R. KONDOLF, a citizen of the United States, residing at Rochester, in the county of Monroe and 5 State of New York, have invented certain new and useful Improvements in Cover-Placing Apparatus for Boxes, of which the following is a specification.

The object of this invention is to provide 10 new and improved means and method for inserting the flanges of a box cover into the pockets provided in the sides and ends of the box body.

A form of box to which this method is 15 especially adaptable is shown in my prior Patent No. 1,234,480 and my pending application Serial Number 228,485.

In applying covers to box bodies which are provided with pockets, such as are shown 20 in my prior patent and application above referred to, it has been found in practice that in making the box body the sides of the pockets are so stiff and lie so closely together that it takes considerable force to 25 spread them apart for the insertion of the cover flanges.

To overcome this difficulty, I provide a means which, when used in the manner hereinafter described, will hold the pockets open 30 and guide the flanges of the cover directly into them.

With this and other objects in view, the method and means will be fully illustrated in the drawings, described in the specification 35 and pointed out in the claims at the end thereof.

In the accompanying drawings:

Figure 1 is a perspective view of one of the hand tools with which the box cover is 40 guided in place on the box body.

Figure 2 is a perspective view of the box partly broken away showing the cover in the process of being placed on the box body.

Figure 3 is a vertical section taken on the 45 line 3^x-3^x of Figure 2.

Figure 4 is a perspective view of a modified form of the tool shown in Figure 1.

In the several figures of the drawings, like reference numerals indicate like parts.

50 The tool shown in Figure 1 comprises a pair of backing plates or guide plates 1 and 2 which are held suitably spaced apart at right angles to each other by means of the bracket 3. The plates 1 and 2 each have a

horizontal channel 4 cut into them near the 55 bottom and have a shoulder 8 formed near the top. The channels are located at the same elevation in each of the plates. Fastened to the backing plate above the channel and on the same side thereof are the 60 knives 5 and 6. These knives overlap the channels 4 and their edges have a shear. The edges of each of the knives 5 and 6 are positioned approximately opposite to the lower edges of each of the channels 4. The 65 knives are beveled and near the lower end are provided with the ridge or bead 7 which serves to spread the pockets inwardly and hold them open while the flanges of the 70 cover are inserted therein.

In practice a pair of these tools are used at one end of the box to spread the pockets and hold them open to receive the flanges of the cover. One of the tools is inserted into the pockets on one corner and the other tool 75 is inserted into the pockets at the adjacent corner of the box. In inserting the tool the lower portion of the backing or guide plates 1 and 2 is placed against the sides of the box. This places the knives in line with the 80 pockets which are to be opened up by them. By forcing the tool downward the knives enter the pockets on either side of the corner and spread them open.

By reason of the shear which is given to 85 the edge of the knife, a corner or point of the knife enters the pocket first, after which the edge enters progressively, opening the pocket as it goes. In the tool shown the knife enters the pocket at the farthest point 90 from the corner and spreads the pocket toward the corner as it descends, although it is obvious that the shear might be inclined in the other direction, in which case the knife would enter the pocket at a point near 95 the corner and open the pocket in the reverse direction. In either case the outer wall of the pocket is sprung into the channel of the tool.

The tools are then left in place while the 100 cover is put on the box. The cover is provided with four flanges which are not connected at the corners, as is shown in Figure 2, the ends of the flanges being beveled. The end flange of the cover is first inserted 105 in the pocket at the opposite end of the box from that where the tools have been applied. The cover is then swung on this

flange as a center, the side flanges entering side pockets and forcing their way into them as the end of the cover is lowered, both the side and end flanges being guided into 5 or toward the pockets by the knives 5. When the end flange reaches the end pocket guided by the knives, it will find that pocket fully opened and will easily sink into it. In this way all the flanges will become seated in the 10 pockets, holding the cover in place. The tools may then be withdrawn, leaving the cover on the box.

It would be understood that the last flange to be inserted is the hardest flange to insert 15 because the inside of the pocket is covered up by it and the operator cannot engage both sides of the pocket to spread it with his fingers and insert the flange at the same time.

20 It will be understood that four tools can be used, one at each corner of the box, which will spread all the pockets and permit all the flanges of the cover to be inserted therein simultaneously. It will also be understood 25 that this type of tool may be machine operated to open the pocket after which the machine can operate to place the cover and withdraw the tools.

I claim:

30 1. A tool for opening a pocket, comprising a backing plate capable of engaging one side of the pocket, a knife carried on the backing plate having an edge held in line with the opening of the pocket when the 35 backing plate engages the side of the box, said backing plate having an open space between it and the knife, capable of receiving a side of the pocket.

2. A knife blade for opening a pocket, 40 said blade having an edge and a bead on the blade near the edge on one side thereof capable of spreading the pocket to receive a

flange therein while the knife remains in engagement therewith.

3. A tool for penetrating the pockets of 45 two adjacent sides of a box near the corner between them, said tool comprising two knives having means for holding them at right angles to each other.

4. A tool for penetrating the pockets of 50 two adjacent sides of a box near the corner between them, said tool comprising two knives having means for holding them at right angles to each other with an open space between them.

5. In a tool for opening two adjacent pockets located at an angle to each other in a box, the combination of a pair of knife blades and a backing plate adapted to support said knife blades and hold them together in fixed position at an angle to each other, with their entering edges at the bottom, the entering edges of said knife blades being slanted to cause similar respective corners of both of said blades to first engage 60 their respective pockets.

6. A tool for opening adjacent pockets in the sides of a box which comprises a pair of knife blades fastened together at an angle to each other, means on said knife blades to 70 force one side of the pocket away from the other side and means to guide a cover flange into the pocket thus opened.

7. A method of placing a flange cover on a box having inner and outer walls which 75 comprises the initial separation of said walls through the penetration between the same of a tool so adapted, said walls supporting said tool for the purpose of guiding the cover flanges between the said inner and 80 outer walls.

In testimony whereof I affix my signature:

MATHIAS R. KONDOLF.
